Term of patent 14 years

(Cl. D26—1)

Fig. 2.

Fig. 3.

Fig. 5.

Fig. 1 is a perspective view of an insulated pigtail connector, showing my new design;

Fig. 2 is a side elevational view, the opposite side having the same appearance;

Fig. 3 is a top plan view;

Fig. 4 is a bottom plan view; and

Fig. 5 is a vertical sectional view taken on the line 5-5 in Fig. 3.

A portion of the drawing figures is diagonally lined to indicate transparency, the inner metal sleeve visible therethrough being stippled to indicate color contrast.

I claim:

The ornamental design for an insulated pigtail connector, as shown and described.
